UNITED STATES PATENT OFFICE.

JOHN B. McCAW, OF NEW YORK, N. Y.

MUFFLER CUT-OUT.

Application filed January 10, 1922. Serial No. 528,129.

To all whom it may concern:

Be it known that I, JOHN B. McCAW, a citizen of the United States, and resident of New York city and State of New York, have invented certain new and useful Improvements in Muffler Cut-Outs, of which the following is a specification.

This invention relates to improvements in muffler cut-outs for use in connection with the exhaust pipes of gasoline or other explosive engines, and may be used either in connection with a stationary engine or an engine mounted upon a moving vehicle, such as an automobile, boat, aeroplane, or other conveyance.

The invention relates particularly to the type of muffler cut-out comprising a separate casing adapted to be installed in the exhaust of the engine to control the flow of the gases whereby they may be directed through a muffler or may be directed through a suitable by-pass and exhausted into the atmosphere in order to relieve any back pressure on the engine cylinder that may arise from causing the exhaust gases to pass through the muffler in the usual course, or by the character of the sound to locate and identify faults of ignition or other defects which interfere with the proper operation of the engine, or to utilize the noise created by the explosions in the engine cylinders and the subsequent escape of the exhaust gases as a warning signal.

The invention consists broadly in the elimination of valves requiring valve-seats, which are exposed to deposits of carbon carried by the exhaust gases which tend to accumulate thereon and interfere with proper seating of the valve and with the control of the exhaust gases and in the substitution of a flexible conduit normally acting as a portion of the exhaust pipe but capable of being deflected out of line with the muffler so as to exhaust the gases directly into the atmosphere.

In the accompanying drawings,

Fig. 1 is a side elevation of my improved muffler cut-out connected to the exhaust pipe and the muffler pipe with the cover in its closed position;

Fig. 2 is a bottom plan view of the same;

Fig. 3 is a sectional side elevation of the cut-out showing the cover in its open position;

Fig. 4 is a cross-sectional view on the line 4—4 of Fig. 2.

The body or casing of the cut-out comprises a central portion 6 and end portions 7 secured respectively to the exhaust pipe 8 and the muffler pipe 9. The casing may be secured to these pipes in any suitable manner, as by being threaded onto the muffler pipe and slipped over the exhaust pipe.

The central portion of the casing is approximately semi-cylindrical in section, with an elongated opening in the bottom. This bottom opening is normally closed by a movable member, preferably forming a lid or cover 10, which is hinged to a pintle 11, 60 preferably formed integral with an extension 12 that forms an actuating arm or lever 13 for the cover. A rod or wire 14 connects this arm or lever with a foot pedal or other actuating mechanism, not shown, 70 whereby the cut-out may be controlled.

The cover is hinged to the casing in any suitable manner, for example, by causing the pintle to pass through an eye 15 formed in a metal strap 16 that is fastened by any suitable means, as a screw 17 engaging a boss 18 formed on the end portion fitted onto the exhaust pipe 8. A strong spring 19 is fixed to the casing and bears against the lid or cover so as normally to hold the 80 same in its closed position. This spring may be held against displacement by the screw 17 which fastens the cover to the casing, and may extend through a small recess 20 provided in the cover adjacent the strap eye 15. 90

Mounted within the casing is a flexible conduit or pipe 21, which is permanently mounted adjacent to the exhaust pipe 8. This conduit is approximately the same or larger in diameter than the exhaust pipe, 95 to permit free passage of the exhaust gases therethrough. The free end of the conduit is movable with the cover and is secured thereto by a suitable fastening device, such as a pair of arms 22 which embrace the 100

sides of the conduit but are cut away flush with the top thereof so as to permit the conduit to rest against the casing and thereby economize space. It is obvious that any suitable fastening means may be employed that will permit the necessary movement of the conduit with respect to such fastening means when the cover is actuated through the connecting arm 13. These arms may be formed integral with the cover or may be formed integral with a block 23 secured to the cover in any suitable manner, as by the screw 24.

The bottom of the casing adjacent to the fixed end of the conduit is cut away on an incline or curve as indicated at 25, to provide a sloping bearing surface for the conduit when it is deflected to prevent breaking by repeated bending over a sharp edge.

Under operating conditions, the cover 10 is normally closed under the action of the spring 19 and the exhaust gases pass through the engine through the exhaust pipe into the flexible conduit, and thence to the muffler. When it is desired to use the cut-out, the cord or wire 14 is actuated from the handle or lever, not shown, to operate the lever 13, which causes the cover to open against the tension of the spring 19. The movement of the cover carries with it the free end of the conduit until it is positioned below the level of the casing, permitting the exhaust gases to escape into the open air. When the arm or lever is released, the cover automatically returns to its closed position under the action of the spring thus aligning the conduit again with the muffler pipe.

By means of my improved construction the necessity for a tightly fitting valve or deflecting plate that will intercept the exhaust gases is entirely avoided. Nor is it necessary to make a close fitting tight joint between the bottom of the casing and the cover, as the principal function of the cover is to control the position of the free end of the flexible conduit. The joint between the conduit and the exhaust is stationary, and may be tight when the parts are assembled. There are no bearing surfaces upon which the carbon deposits from the exhaust gases may accumulate and interfere with the operation of the device. A comparatively short length of flexible pipe is sufficient to provide for the deflection necessary to direct the exhaust gases below the bottom of the cut-out, but it is obvious that a pipe of any desired length within the limits of the casing may be used.

What I claim as my invention is:

1. A cut-out for automobiles comprising a body portion communicating at one end with the exhaust pipe, a flexible conduit mounted within the casing and means for moving said conduit to control the move-

ment of said exhaust gases within the casing.

2. In a muffler cut-out, the combination with a casing communicating with the exhaust pipe and a muffler pipe, of a flexible conduit fixed at one end to intercept the gases from the exhaust pipe, the opposite end of said conduit being free, and means for moving said conduit into and out of line with the muffler pipe.

3. In a muffler cut-out, the combination of an exhaust pipe, a muffler pipe fixed in substantial alignment with the exhaust pipe, a flexible member provided with a passage for the exhaust gases secured in fixed relation to one of said pipes and communicating therewith, and means for moving said member into and out of communication with the other pipe, substantially as described.

4. In a muffler cut-out, the combination with an exhaust pipe comprising a plurality of sections, one of said sections being fixed to and communicating with the engine and the other section communicating with the muffler, of a flexible intermediate section provided with a passage for the exhaust gases, means for normally holding said section in communication with the adjacent sections, and means for moving said section out of alignment with one of its adjacent sections thereby to discharge said gases into the atmosphere.

5. In a device of the character described, the combination of a casing, an exhaust pipe having a flexible conduit connected thereto, an opening in said casing communicating with a muffler, a separate opening in said casing, a cover for said opening and a flexible conduit communicating with the exhaust pipe and movable with said cover to control the direction of the flow of the gases through said openings respectively.

6. In a muffler cut-out, the combination of a casing communicating at one end with an exhaust pipe, a plurality of openings in said casing, a flexible conduit fixed at one end of the casing to intercept the gases from the exhaust pipe and deliver them to said openings, a movable member on said casing, means on said movable member engaging the conduit, and means for actuating said member.

7. In a muffler cut-out, the combination of a casing, a flexible conduit in said casing communicating with an exhaust pipe, said casing being provided with an opening adapted to communicate with a muffler pipe and provided with a separate by-pass opening, a movable member pivoted to the casing, means on the cover engaging the conduit, loosely to permit relative movement thereof, and means for actuating the cover to move said conduit into alignment with the muffler opening and the by-pass opening respectively.

8. In a muffler cut-out, the combination of a casing communicating at one end with an exhaust pipe, a plurality of openings in said casing, a flexible conduit fixed at one end of the casing to intercept the gases from the exhaust pipe and deliver them to said openings, a movable member on said casing, means on said movable member engaging

the conduit to deflect the same, a curved bearing surface on the casing to engage the conduit in its deflected position. 10

Signed at New York, in the county of New York and State of New York, this 7th day of January A. D. 1922.

JOHN B. McCAW.
